UNITED STATES PATENT OFFICE.

JAMES J. MASON, OF CISCO, CALIFORNIA.

TELEGRAPH-KEY.

1,302,401.

Specification of Letters Patent. Patented Apr. 29, 1919.

Application filed May 23, 1917. Serial No. 170,398.

To all whom it may concern:

Be it known that I, JAMES J. MASON, a citizen of the United States, and resident of Cisco, in the county of Placer and State of California, have invented certain new and useful Improvements in Telegraph-Keys, of which the following is a specification.

This invention relates to telegraphy and has more especial reference to an improved key for transmitting intelligence.

The invention has for its dominant object to provide a telegraph key, the inherent resiliency of which will allow the same to be advantageously used for sending messages in a rapid and distinct manner without strain upon part of the operator.

Another object of the invention is to provide an anti-friction bearing for the key, whereby friction will be eliminated to the greatest possible extent and as a consequence, easy operation of the key insured.

Among other aims and objects of the invention may be recited, the provision of a key of the character mentioned with a view to compactness, and in which the number of parts are few, the construction simple, the cost of production small, and efficiency and operation high.

Other and further improvements and novel details in the construction and arrangement of parts will be appreciated from the description to follow, which for a clear understanding of the invention should be considered in connection with the accompanying drawings forming a part hereof and wherein the preferred embodiment of the invention is shown for the purpose of illustration.

In the drawings:

40 Figure 1 is a side elevation of the improved key;

Fig. 2 is a detail in perspective of the lever thereof; and

Fig. 3 is a fragmentary detail in section showing one of the anti-frictional bearings for the lever.

Similar characters of reference are employed in all of the above described views to indicate corresponding parts.

50 Referring more specifically to the drawings, 1 designates the base of the key in which

oppositely disposed dove-tailed grooves are formed and are adapted to receive stands 2 having their lower ends formed complementally to the said dove-tailed grooves. Set 55 screws 3 are turned into engagement with vertically disposed openings and are adapted to engage the bases of the several stands whereby the same can be secured in adjusted positions upon the base 1.

Within the upper ends of the slidable stands or supports 2 pockets having the side walls thereof screw threaded are formed and have turned into engagement therewith bearing cups 4, the ball bearings 5 of which 65 are adapted to support the bearing pintles of the key lever which will be subsequently described.

The key shown in the present embodiment is of the legless type and has arranged 70 upon the base 1 a binding post 6 whereby one side of the intelligence transmitting circuit may be engaged therewith. A shut off switch 7 being pivotally engaged with the binding post 28, hereinafter described and 75 is adapted to contact with the terminal 8 arranged upon the forward portion of the base and insulated therefrom, movement of said shut off being facilitated through the medium of an insulated handle 9.

80 A lever 10 is provided and has the opposite ends thereof provided with spaced spring arms 11 and 12, the latter, which are formed upon the forward portion of the lever, having a solid offset piece 13 formed 85 upon their outer ends whereby a finger button 14 formed of soft rubber and provided with a screw threaded shank can be engaged therewith. Transversely disposed bearing pintles 15 having tapered ends 16 are formed 90 intermediate the lever 10 and as heretofore stated are received upon the bearings 5 contained in the cup 4.

To permit the tension of the lever 10 to be regulated, openings 17 are formed in the 95 upper spring arms 11 and 12 while screw threaded openings 18 are formed in the lower spring arms 11 and 12 in direct alignment with the openings 17 and, obviously, permit the passage of set screws 19 and 20 100 therethrough. As will be noted, the screw threaded shank of the set screw 19 is of a

greater length than the shank of the set screw 20, thereby permitting the same to serve as an adjusting screw whereby the vibratory movement of the lever 10 may be regulated accordingly. A locking nut 21 being turned thereon and having bearing upon the uppermost spring arm 11 whereby the tension thereof may be adjusted. The screw threaded shank of the set screw 20 is provided with a bearing pin 22 which pin receives thereabout the uppermost convolution of a coil spring 23 seated upon the base 1, while a locking nut 24, similar to the locking nut 21 is arranged upon the said set screw, and as will be understood, allows the tension of the spring arms 12 to be adjusted accordingly.

Upon the lowermost of the spring arms 12 and substantially intermediate its ends a contact point 25 is mounted and is adapted to be engaged with the contact formed upon the terminal 8 whereby the making and breaking of the intelligence transmitting circuit will be permitted.

25 A screw threaded pocket 26 is formed in the transversely disposed bearing portion of the lever 10 and receives therein a set screw 26', this set screw serving as a contact terminal for the remaining side of the intelligence transmitting circuit and supplying energy to the contact 25 by way of the conductor 27 thereby allowing the intermittent making and breaking of the same in order that the usual dots and dashes may be transmitted thereby.

30 A second binding post 28 is arranged upon and insulated from the base and is connected with the contact 8 by means of an insulated wire not shown, arranged beneath the said base.

35 In operation, upon depression of the finger button 14, the intelligence transmitting circuit will be closed due to the contact of the points 8 and 25. Upon the release of pressure the lever will be automatically returned to its normal or inoperative position by means of the coil spring 23, the tension of which is adjusted by varying the positioning of the set screw 20 with relation thereto. Obviously, the duration of contact between the points 8 and 25 is varied in order that the usual dots and dashes composing the telegraphic code may be transmitted thereby. To remove the slidable stands 2 in order that the bearings 5 may be cleaned or oiled, it is only necessary to loosen the set screws 3 whereupon the said stands may be readily moved out of engagement with the tapered ends of the bearing pintles 15. To vary the tension of the spring arms 11 and 12 formed upon the lever 10, the locking or adjusting nuts 21 and 24 are turned downwardly upon the shanks of the set screws 19 and 20 accordingly.

From the foregoing, it will be understood by workers in the art that with my improved key, friction is eliminated to the greatest possible extent and as a consequence wear upon the points of friction will be materially lessened thereby prolonging the life of the same. The lever by being split over the contact point offers a spring which will enable the operator to rapidly and distinctly transmit messages by means of the instrument, the same being capable of being "rolled" in a manner similar to a drum, while due to the provision of the spring arm 11, the contact jar or shock to the operator's hand will be obviated, thereby lessening the liability of what is termed "operator's paralysis." Further, by the provision of the soft rubber finger button 14 additional resiliency will be embodied by the key.

Obviously, the construction shown is capable of considerable modification, the key being readily adaptable for use upon the ordinary leg type, and therefore such modification as is within the scope of my claims, I consider within the spirit of my invention.

I claim:

1. A telegraph key having one end of the lever thereof split longitudinally and between the upper and lower sides thereof, and bearings formed on the intermediate portions of the lever.

2. A telegraph key including a lever having superposed spring arms formed upon its ends and bearings formed upon the intermediate portion of the lever.

3. A telegraph key including a lever having superposed spaced spring arms formed on the ends thereof, and bearing pintles carried upon the intermediate portions of the lever.

4. A telegraph key including a lever having bearing pintles formed upon the intermediate portion thereof, anti-frictional bearings for said pintles, the opposite end of the lever being split and having the divided portions thereof arranged in superposed relationship, and means engaged with said split ends for adjusting the tension of the same.

5. A telegraph key including a lever having superposed spaced spring arms formed on the ends thereof, means for adjusting the tension of said arms, bearing pintles formed intermediate the ends of the lever, and anti-frictional bearing means for supporting said pintles.

6. A telegraph key including a lever having superposed spaced spring arms on the ends thereof, means for adjusting the tension of said arms, slidable stands arranged upon the key base, and anti-frictional bearing means carried by said stands for receiving the pintles.

7. A telegraph key including a lever having superposed spaced spring arms on the

ends thereof, and a resilient finger button secured to certain of said ends.

8. A telegraph key including a lever having superposed spaced spring arms on the 5 ends thereof, means engaged with said arms for adjusting the tension of the same, bearing pintles formed intermediate the ends of the lever, slidable stands formed on the key

base, anti-frictional means carried by said stands for receiving the pintles, and a re- 10 silent finger button secured to certain of the ends of the lever.

In testimony whereof, I affix my signature hereto.

JAMES J. MASON.
